Herbert Ogden

UNITED STATES PATENT OFFICE.

JOHN E. GOODWILLIE, OF BROOKLYN, NEW YORK, ASSIGNOR TO INGERSOLL-RAND COMPANY, OF JERSEY CITY, NEW JERSEY, A CORPORATION OF NEW JERSEY.

SURFACE CONDENSER.

Application filed April 11, 1925. Serial No. 22,250.

To all whom it may concern:

Be it known that I, JOHN E. GOODWILLIE, a citizen of the United States, and a resident of the borough of Brooklyn, city of

5 New York, county of Kings, and State of New York, have invented a certain Surface Condenser, of which the following is a specification accompanied by drawings.

This invention relates to condensers, but 10 more particularly to that type of condenser known as surface condenser, wherein a plurality of water tubes extending through a chamber transverse to the current of steam to be condensed, provide cooling surface 15 for absorbing heat to condense the steam.

Ordinarily in a surface condenser of this type, the cross section of the steam chamber is substantially the same throughout. However, the capacity for condensing steam 20 is not the same in the various sections for the reason that the water flowing in the cooling tubes is cooler at one end of the condenser than at the other, being warmed as it passes through the tubes by the absorption of heat from the steam. Thus, ordinarily that part of the condenser nearer the water inlet end of the tubes has a greater 25 capacity for condensing steam than that portion of the condenser nearer the water outlet.

It is also found that unless special provision is made, the steam at the cooler end of the condenser will not penetrate to the last row of tubes if the vacuum is such as 30 to insure the steam reaching no farther than the last row of tubes at the warm end of the condenser. There is thus, a certain area at the cool end of the condenser which performs no useful function since it is not 35 reached by the steam. One way of expressing this is to say that steam penetration at the warmer end is deeper than at the cool end. It is proposed by this invention to provide means to cause the steam to penetrate 40 the entire tube nest in all sections of the condenser.

The object of this invention is to provide additional cooling tubes at the warmer end of the condenser in such a manner as 45 to increase the depth of the condenser at the warm end, in other words, to increase the length of the path of the steam at the warm end to such an extent that when the steam is drawn into the condenser to the last bank of tubes at the warm end, the

steam will also be drawn to the last bank of tubes at the cool end. In this case there will be substantially no waste or useless cooling surface provided.

The invention will be more clearly understood by reference to the drawing in which there is illustrated, a surface condenser of the water tube type constructed in accordance with the practice of the invention.

The condenser is shown in vertical longitudinal section to more clearly show the internal arrangement of parts.

The casing A is provided with an inlet B to admit the steam, and outlets C and C' through which the condensate and incondensable gases are drawn out by means of a vacuum pump or other exhausting apparatus (not shown). The steam is condensed by contact with water tubes D extending from end to end of the casing A transverse to the direction of flow of the steam. The ends of the water tubes D are suitably sealed in tube sheets E and communicate at the inlet end with a water head F and at the discharge end with a water head G.

As the water flows through the tubes D, it is heated, its temperature is raised by the heat absorbed by the condensing steam so that one end of each tube is cool as compared with the other end. The difference in temperatures at the two ends may vary somewhat under the operating conditions. Ordinarily, the temperature difference at the ends of the condenser may be 10° Farenheit, more or less.

It follows that the condensing surface at the two ends of the tubes have different capacities for condensing steam, that at the cool end being greater because of its lower temperature. If it be considered that the same quantity of steam passes to both ends of the condenser, then the penetration of the live steam will be greater at the warm end of the condenser than at the cool end because the cool end of the condenser has the greater capacity for absorbing the heat of vaporization from the steam, the water being at a lower temperature.

It is understood that the steam is drawn through the banks of tubes D by the exhausting apparatus associated with the outlet C and that as high a degree of vacuum as is practical, is maintained thereby at that outlet. Thus, if sufficient supply of steam is admitted at the inlet B, the steam will penetrate

trate at the warm end of the condenser at least to the lowermost bank of tubes D while under these conditions the steam will not penetrate to the same depth at the cool end 5 of the condenser because of the more rapid condensation at the latter end.

Under these conditions also, there will then be a certain depth at the cool end beyond which the cooling tubes are practically 10 useless, since the condenser should be designed so that substantially no steam will pass to the outlet through the warm end. The condenser may therefore be built smaller and still be able to accommodate the steam 15 to be condensed provided that all of the condensing surface of the water tubes D is utilized.

To this end the invention contemplates the use of additional banks of water tubes 20 H, at the warm end of the condenser. The entire cooling surface of all of the tubes D and H may thus be used for the purpose of condensing the steam, since there is thus permitted a greater depth of steam penetration 25 at the warm end than at the cool end so as to substantially equalize the condensing capacity at both ends of the condenser.

A separate water head J may be employed 30 to supply cooling water to the tubes H, there being also a tube sheet K for sealing the ends of the tubes H at this head. The provision of separate water heads F and J permits separate control of the flow of cooling 35 water in the tubes D and H, as under some circumstances, it may be desirable to maintain less velocity of flow in the tubes H than in the tubes D.

As is usually the case in condensers having 40 long tubes, a tube support in the form of a plate O is provided. The plate O may, in this instance, perform the function of a partition dividing off the cool zone or end 45 of the condenser from the warm end, thereby maintaining separate compartments, in one of which the tubes are comparatively cool and have a greater steam condensing ca-

pacity, and the other being the warm section in which there are a greater number of tubes, the upper tubes being of less capacity 50 for condensing steam in the warmer end.

The condenser, above described, is thus divided into two zones of equal steam condensing capacity, each capable of being utilized over the entire water tube condensing 55 surface without steam penetration beyond the last bank of tubes. Other arrangement of the supplementary tubes H, for accomplishing this purpose, will become apparent 60 for those skilled in the art without departing from the scope of the invention.

I claim:

1. A surface condenser, comprising a steam inlet and an outlet for condensate, longitudinal water tubes extending through 65 the casing transverse to the direction of flow of the steam, and means for increasing the steam condensing capacity of the warmer end of the condenser to substantially equal the steam condensing capacity of the cooler 70 end.

2. A surface condenser, comprising a steam inlet and an outlet for condensate, longitudinal water tubes extending through 75 the casing transverse to the direction of flow of the steam, and means for substantially equalizing the steam condensing capacities at the two ends of the condenser, including supplementary tubes located at the warmer end of the condenser.

3. A surface condenser, comprising a steam inlet and an outlet for condensate, longitudinal water tubes extending through 85 the casing transverse to the direction of flow of the steam, and means for substantially equalizing the steam condensing capacities at the two ends of the condenser, including supplementary tubes to permit greater depth 90 of steam penetration at the warm end of the condenser.

In testimony whereof I have signed this specification.

JOHN E. GOODWILLIE.
